UNITED STATES PATENT OFFICE

HAROLD LANGLEY BLOOD, OF OAK PARK, ILLINOIS, ASSIGNOR TO WESTERN ELECTRIC COMPANY, INCORPORATED, OF NEW YORK, N. Y., A CORPORATION OF NEW YORK

WIREDRAWING APPARATUS

Application filed June 8, 1927. Serial No. 197,297.

This invention relates to wire drawing apparatus, and more particularly to the mounting of dies in wire drawing apparatus.

In the practice of drawing wire through dies mounted in a fixed position, it has been found in some instances that extreme care must be exercised to prevent the formation of a deleterious deposit of metallic dust within the die opening, which might cause the production of rough non-uniform wire and result in considerable breakage. Maintaining the dies in a fixed or stationary position also usually confines the wire to a localized portion of the capstan surface, tending to wear grooves therein and necessitate premature replacements of the capstan.

The primary object of the invention is to provide a simple, durable and efficient means for speedily drawing wire of uniform and accurate cross-section.

In order to attain this and other objects, and in accordance with the general features of the invention, one embodiment thereof includes a shelf or holder resting on ball bearings and which is adapted to support a plurality of drawing dies. A circular motion is imparted to the shelf by an eccentric arrangement, which causes the wire as it is drawn through the supported dies by a suitable capstan to travel backward and forward across the face of each step of a stepped capstan. In addition, this arrangement keeps the mouth of the die clean by moving the wire with a wiping action around the entire circumference of the draw hole of each die.

Other objects and advantages of this invention will be apparent from the following detailed description taken in connection with the accompanying drawing, in which—

Fig. 1 is a fragmentary front elevational view, partially in section, of a wire drawing apparatus of a well known type in which is incorporated one embodiment of the invention;

Fig. 2 is a plan sectional view taken on the line 2—2 of Fig. 1;

Fig. 3 is a vertical sectional view taken on line 3—3 of Fig. 2, and

Fig. 4 is an enlarged fragmentary detailed view of one of the wire drawing dies seated within a companion shelf showing in dot and dash lines some of the various positions assumed by the die during the movement of the shelf.

Referring now to the drawing, wherein like numerals have been employed to designate similar parts throughout the several views, and which illustrates the invention as applied to a well known type of wire drawing machine such as is disclosed in detail in Patent 1,599,393, issued September 7, 1926 to H. Blount, only such portions of the machine being shown as are essential to a complete understanding of the invention, upper and lower shelves or holders 10 and 11 are provided which are adapted to support a plurality of wire drawing dies 13 of any suitable type. The die shelves 10 and 11 are supported by a bracket 14 which is fastened to the machine frame 15 in any suitable manner, such as by screws 16. These shelves are supported by and slidably between steel balls 17 located in circular recesses 18 provided in the upper and lower surfaces of each shelf, and motion is imparted thereto by eccentrics 19 secured to a pair of rotatable vertical shafts 20 carrying gears 21 which mesh with companion worm gears 22 secured to a horizontal power shaft 23. This shaft 23 is mounted, at one extremity, in a bearing 24 in the machine frame 15, and rotation is imparted to the shaft 23 by a driving gear 25 which is operatively connected with the shaft through a gear 26 and a sprocket chain 27. The driving gear 25 may be connected in any suitable manner with the mechanism (not shown) which actuates the conventional stepped capstan 28 positioned immediately beneath the shelf 11. From the foregoing

80
85
90

it will be understood that when the driving gear 25 is rotated the eccentrics 19 operate to cause the shelves 10 and 11 and the dies 13 carried thereby to experience a circulatory movement.

5 In the operation of the machine a wire 29 is strung through the dies 13 and thence around conventional idler pulleys 30 above the die shelf 10 and around the stepped capstan 28. From the foregoing description it 10 will be understood that when the driving gear 25 rotates, the capstan 28 will also rotate and draw the wire 29 through the dies 13 which at the same time are moving in a 15 circular path, as clearly shown in Fig. 4 wherein the dot and dash lines represent the outline of one of the dies 13 during various periods of a complete cycle. Since the upper portions of each pass of the wire are maintained in relatively fixed positions within the 20 grooves of the idler pulley 30, this circulatory movement imparted to the dies causes the wire 29 to travel backward and forward across the entire width of each step in the capstan, 25 thus preventing the wearing of grooves therein. This circulatory movement of the dies also causes the wire 29 passing there- 30 through to wipe the entire circumference of the die mouth, thereby precluding the accumulation of injurious deposits therein, such as metallic dust. A compound chamber 32, which may be fed in any suitable manner, is mounted upon the die shelf 10 and is provided with spouts 33 and 34 to per- 35 mit of the forcible ejection of a lubricant into the die faces, thereby serving to wash away material loosened by the wiping action of the wire and to effectively lubricate the wire.

40 What is claimed is:

1. In a wire drawing apparatus, a die holder, a die supported by the holder, means for drawing wire through the die, and means for imparting a rotary movement to the die 45 to reciprocate the wire drawn therethrough across the face of the drawing means and to wipe the mouth of the die with the wire.

2. In a wire drawing apparatus, a movable die holder, a die supported by the holder, 50 means for drawing wire through the die, and means for causing the opening in the supported die to be moved in an arcuate path to reciprocate the wire drawn therethrough across the face of the drawing means and to 55 wipe the opening of the die with the wire.

3. In a wire drawing apparatus, a movable die holder, a die supported by the holder, an element for drawing wire through the die, and means for moving the die in a rotary path 60 to effect a wiping action between the orifice of the die and the wire drawn therethrough and to reciprocate the wire across the surface of the drawing element.

4. In a wire drawing apparatus, a movable holder for carrying a die, means for

drawing wire through the die, an eccentric mechanism for imparting a rotary movement to the die holder, and means for driving the eccentric to move the die in a circular path to move the wire transversely to the direction of drawing and to wipe the 70 circular orifice of the die with the wire.

5. In a wire drawing apparatus, a support, a die holder slideable therein, friction reducing means associated with the holder, 75 mechanism for moving the holder, and means for actuating the mechanism.

6. In a wire drawing apparatus, a support, a plurality of parallel die shelves slideable in the support, friction reducing means 80 associated with each shelf, eccentric mechanisms for moving the shelves in a circulatory path and common means for actuating the eccentric mechanisms to effect a synchronous movement of the shelves.

7. In a wire drawing apparatus, a support, a pair of horizontally disposed parallel die shelves slideable in the support, ball bearings interposed between each shelf and the support, a rotatable shaft provided with eccentrics at each end thereof for actuating the shelves, a worm gear on the shaft, a drive shaft having a worm engaging the gear on the rotatable shaft, and means for rotating the drive shaft.

8. In a wire drawing apparatus, a support, a die holder movable therein, a die mounted in the holder for drawing wire, mechanism for moving the holder in a circulatory path, and means for communicating power to the 100 mechanism to move the holder and the die in a circulatory path to reciprocate the wire transversely to its direction of drawing and to effect a wiping action between the die and the wire.

9. In a wire drawing apparatus, a support, a die shelf slideable in the support, a die carried by the shelf for drawing wire, mechanism for moving the shelf in a substantially rotary path, and means for communicating power 110 to the mechanism to move the shelf and the die in a rotary path to move the wire transversely to its longitudinal axis and to effect a wiping action between the draw hole of the die and the wire.

10. In a wire drawing apparatus, a support, a die shelf slideable on the support, a drawing die carried by the shelf, a drawing capstan, a shaft, an eccentric mounted on said shaft, means on said shelf operatively associated with said eccentric, and means for rotating the shaft to impart a rotary movement to said shelf and to the die carried thereby to reciprocate the wire across the face of the capstan and to wipe the mouth of the die with 120 the wire.

11. In a wire drawing apparatus, a support, a plurality of die holders movable in the support, a plurality of dies mounted in the holders for reducing wire drawn there- 130

through, eccentric mechanisms for moving the holders in a rotary path, and means for actuating the eccentric mechanisms to effect a synchronous movement of the holders to simultaneously move the dies in a rotary path to move the wire transversely to the direction of drawing and to wipe the mouths of the dies with the wire.

In witness whereof, I hereunto subscribe
10 my name this 31st day of May, A. D., 1927.

HAROLD LANGLEY BLOOD.
